SANITARY HYGIENIC DEVICE FOR
TELEPHONE INSTRUMENTSLawrence Frederick Richardson, Stanmore, and
Vivian John Faulkner, Harrow, EnglandApplication April 21, 1939, Serial No. 269,072
In Great Britain April 22, 1938

3 Claims. (Cl. 179—185)

This invention relates to a sanitary or hygienic device for a telephone instrument of what is known as the hand-microphone type, and comprises an absorbent pad or the like adapted to be resiliently carried by the supporting stand of the instrument and to close the mouthpiece or earpiece when the instrument is placed on the stand.

Preferably two such pads are adapted to be pivotally carried by the stand about parallel axes, each such axis being positioned approximately both in the general plane of the mouthpiece (when adjacent) and in that of the earpiece (when adjacent), and the pads being upwardly spring-pressed, so that in either position of the instrument on its stand its mouthpiece and earpiece are both closed by the pads.

The following description and accompanying drawings, which are given by way of example only, have reference to devices incorporating two pads arranged in this way. Of the drawings:

Figure 1 is a plan view of a device constructed separately from the telephone stand for attachment thereto.

Figure 2 is a side elevation showing the device attached to a stand and co-operating with the instrument.

Figure 3 is a sectional view of the pad in its holder, and

Figure 4 is a view similar to Figure 2, but showing an alternative device in which the pads are directly carried by the stand.

Each pad 1 is fitted in a shallow circular holder 2 having a central nipple 3 (see Figure 3) through which air may circulate to carry vapour from the pad into and round the mouthpiece or earpiece. The pad itself may be constructed of any suitable material, for example felt or cotton-wool covered with gauze or plush, or it may be a solid block of evaporating chemical, and incorporates a backing disc 4 having a central hole to give a firm push fit over the nipple 3.

The pad holders 2 are hinged at 5 to opposite ends of a rectangular collar member 6 adapted to be fitted firmly around the neck of the stand

7 of the telephone, as shown in Figure 2. For this purpose the collar portion may be made in two halves adapted to interlock by dovetail joints at 8, and if (as is contemplated) the member 6 and pad holders 2 are made by moulding from a synthetic resin type of material the halves of the collar will have a slight "spring" and render the dovetail joints 8 entirely satisfactory in operation. Alternatively, of course, the collar member 6 might be open or hinged at one side and

slipped around the neck of the stand 7 from the side, being held in position by suitable clamping or frictional gripping means.

As will be seen from Figure 2, the arrangement is such that when the device is fitted each hinge 5 is so placed that its pad will lie either in the general plane of the earpiece 9 or the mouthpiece 10 of the hand instrument 11, whichever is adjacent, so that both these are neatly closed by the pads in whichever position the instrument is replaced. Each pad is, of course, supported against the earpiece or mouthpiece by a wire spring 12 at its hinge 5, a stop piece 13 being incorporated in the hinge to prevent the pad rising substantially above the horizontal 15 when the instrument is in use. It will also be understood that the springs 12 are of a light nature so as not to prevent the instrument from depressing its cradle properly when it is replaced.

The pad holders might of course be carried directly by the stand 7 in various ways. Thus, as indicated in Figure 4, they could each be carried by a resilient wire stem 14 rising from the base of the stand 7, each wire 14 being swan-necked to give the same effect as the special disposition of the hinges 5.

We claim:

1. A sanitary device for a telephone apparatus of the hand telephone type, comprising two absorbent pads, two identically shaped pad holders for said pads, and means for supporting said pad holders on the stand of a hand telephone at a distance from one another equal to that between the mouthpiece and the earpiece of the hand telephone and resiliently holding both said pads in a common horizontal plane substantially coinciding with the rim of the earpiece when the hand telephone is placed on its cradle, each of said pad holders being adapted to tilt downwardly about a horizontal axis and to yield to the mouthpiece of the hand telephone when the latter is placed on the cradle, whereby in either position of the hand telephone on the cradle the mouthpiece and the earpiece are closed by said pads.

2. A sanitary device for a telephone apparatus of the hand telephone type, comprising two absorbent pads, two identically shaped pad holders for said pads, an elongated carrier for said pad holders having its ends spaced a distance equal to that between the mouthpiece and the earpiece of a hand telephone and being adapted to be mounted on the stand of a hand telephone in a position in which its ends are disposed in a common plane substantially coinciding with

- the rim of the earpiece when the hand telephone is placed on its cradle, said two pad holders being pivoted about parallel horizontal axes to the two opposite ends of said carrier, respectively, and spring means holding said two pad holders normally in said common horizontal plane whereby either of them can yield to the mouthpiece of the hand telephone when the latter is placed on the cradle.
3. A sanitary device for a telephone apparatus of the hand telephone type, comprising two absorbent pads, two identically shaped pad holders for said pads, a collar adapted to be mounted on the base of the stand of a hand telephone, and two resilient wire stems rising from diametrically opposite points of said collar and being

slightly inclined towards one another, the upper ends of said wire stems being bent outwardly and supporting said pad holders at a distance from one another equal to that between the mouthpiece and the earpiece of the hand telephone so as to hold both said pads resiliently in a common horizontal plane substantially coinciding with the rim of the earpiece when the hand telephone is placed on its cradle, whereby each of said pad holders may tilt downwardly about a horizontal axis to yield to the mouthpiece of the hand telephone when the latter is placed on the cradle.
